UNITED STATES PATENT OFFICE.

JOHN A. GULLERY, OF BROOKLYN, NEW YORK.

NIPPLE-PROTECTOR.

1,258,766.

Specification of Letters Patent. Patented Mar. 12, 1918.

Application filed May 1, 1915, Serial No. 25,256. Renewed July 20, 1917. Serial No. 181,858.

To all whom it may concern:

Be it known that I, JOHN A. GULLERY, a citizen of the United States, residing at Brooklyn, in the county of Kings and State of New York, have invented new and useful Improvements in Nipple-Protectors, of which the following is a specification.

This invention relates to sanitary protectors for bottle nipples and it consists in the novel features hereinafter described and claimed.

An object of the invention is to provide a nipple protector of simple structural arrangement adapted to be applied to and house the nipple while the same is in position upon the neck of a bottle.

With the above objects in view the protector consists of two sections of thin metal, preferably aluminum, hingedly connected together at one side and provided with means for securing the opposite side edges together. The said sections are of such size that when they are closed together the major portion of the inner surface of the protector is spaced from the outer surface of the nipple, consequently the application of the protector will not distort the shape of the nipple nor is it in such close proximity to the same as to produce rust or corrosion at the inner side of the protector or mildew upon the nipple in the event that either of the parts is damp when brought together. The sections are provided at their lower ends with out-standing skirt portions which are disposed beyond the outer side of the bead of the nipple and prevent dust or other foreign substance from settling upon the same. When the nipple is applied to the neck of the bottle the bead at the mouth of the bottle swells the intermediate portion of the nipple and the protector is provided with an inwardly disposed annular ridge which is adapted to lie between the said swell and the bead of the nipple whereby the protector is held against longitudinal movement with relation to the nipple when applied.

In the accompanying drawing:—

Figure 1 is a side elevation of a bottle with a nipple thereon and the protector applied and shown in section.

Fig. 2 is a transverse sectional view of the protector.

Fig. 3 is an enlarged detailed sectional view of portions of the protector illustrating the means whereby the free edge por-

tions of the sections may be adjustably secured together.

As illustrated in the accompanying drawing the bottle 1 is of the usual nursing type and is provided at its mouth or the end of its neck with an annular out-standing bead 2 indicated by dotted line in Fig. 1 of the drawing. The nipple 3 may be of any conventional form or type and is composed of elastic flexible material such, for instance, as rubber. The nipple 3 is provided at its larger end with an outstanding annular bead 4. When the nipple 3 is applied to the neck of the bottle 1 the bead 4 surrounds the neck thereof and inasmuch as the bead 3 is inserted in the intermediate portion of the nipple 3 the said intermediate portion is bowed outwardly forming a swell 5.

The protector includes metallic sections 6 and 7 struck up from thin metal, preferably aluminum, and the said sections are hingedly connected together at one side edge as at 8. The section 6 is provided at its free edge with an offset flange 9 having at its inner edge notches 10. The section 7 is provided in the vicinity of its free edge with an out-standing rib 11 adapted to enter one of the notches 10 when the free edge portions of the sections 6 and 7 are brought together. When the free edge portions of the sections 6 and 7 are closed together the edge portion of the section 7 fits behind the flange 9 and the rib 11 may enter any one of the notches 10 and inasmuch as the said notches are arranged in a row disposed circumferentially with relation to the protector the said securing means permits the protector to be applied to bottles which vary slightly in diameter at their neck portions. The sections 6 and 7 are provided at their lower ends with skirt portions 12 which are greater in diameter than the bead 4 and which stand out from the outer surface of the bead when the protector is applied and which serve as means for preventing dust or other substances from settling upon the bead. At the upper ends of the skirt portions 12 the sections 6 and 7 are provided with inwardly disposed ridges 13 which lie between the bead 4 and the swell 5 of the nipple when the protector is applied and which serve as means for preventing the protector from moving longitudinally with relation to the nipple. When the protector is applied the said ridges are the only por-

tions of the sections which come in contact with the nipple. Immediately above the ridges 13 the sections 6 and 7 are provided with outwardly bowed portions 14 which receive the swell 5 of the nipple when the protector is applied to the same and the upper portions of the sections 6 and 7 conform in general to the upper part of the nipple 3 and completely house the same when applied.

10 Therefore it will be seen that when the protector is in position upon the nipple, the surface of the nipple which is used is completely inclosed and is spaced from the inner surface of the protector. Consequently

15 the nipple is protected from foreign substances and the space mentioned incloses a volume of air which prevents the formation of rust or corrosion upon the protector and also prevents the formation of mildew upon

20 the nipple. Consequently the nipple is maintained in a sanitary condition and the

protector may be readily detached from the same when it is desired to use the bottle.

Having described the invention what is claimed is:—

25 A nipple protector comprising metallic sections hingedly connected together, means for securing the sections in closed position with relation to each other, the sections being provided at their lower ends with outwardly disposed skirt portions and having inwardly disposed ribs located above the skirt portions and provided with outwardly bowed portions located above the said inwardly disposed ribs.

30 In testimony whereof, I affix my signature in presence of two witnesses.

35 JOHN A. GULLERY.
